UNITED STATES PATENT OFFICE.

BENJAMIN G. LUTHER, OF WORCESTER, MASSACHUSETTS.

RAILWAY CUT-OFF SAW.

Specification forming part of Letters Patent No. 714,314, dated November 25, 1902.

Application filed May 26, 1902. Serial No. 109,084. (No model.)

To all whom it may concern:

Be it known that I, BENJAMIN G. LUTHER, a citizen of the United States, residing at Worcester, in the State of Massachusetts, have 5 invented a new and useful Improvement in Railway Cut-Off Saws, of which the following is a specification.

The nature of my invention consists in improved mechanism for raising and lowering 10 the saw automatically and operating the saw-carriage, as hereinafter fully set forth.

In the accompanying drawings, Figure 1 represents a side elevation of a sawing-machine embodying my improvement. Fig. 2 15 represents a top view with the same without the saw-table for holding the board. Fig. 3 represents a section taken in the line 3 3 of Fig. 2. Fig. 4 represents a section taken in the line 4 4 of Fig. 2.

20 In the drawings, A represents the frame of the machine, and B the saw-table supported from the frame A by means of the standards C C, located at the corners of the table. The saw D is arranged to rise and fall at the edge 25 of the table and is held upon the arbor E, which is journaled in the tilting frame F, the said frame being pivoted upon the inwardly-extending hubs a of the boxes G G of the traveling saw-carriage H, and within the said 30 boxes G G is journaled the shaft I, upon which is secured the pulley J, which is driven from the driving-pulley K by means of the belt K', and upon the shaft I at the side of the pulley J is placed the gear L, which engages 35 with the pinion L' upon the saw-arbor E, the said pinion being preferably made of rawhide or similar material, whereby the operation of the gears will be made noiseless. The carriage H is guided upon the track H' by means of 40 the grooved wheels b b, the opposite side of the said carriage being provided with the plain wheels b' b', which run upon the plain track H² of the machine-frame. The belt K', which drives the pulley J from the driving- 45 pulley K, passes around the idler-pulley K², the shaft K³ of which is held in suitable hangers K⁴, attached to the under side of the carriage H, and from the pulley K² the belt passes around the adjusting-pulley K⁵, the 50 said pulley being held between the parallel arms M M, secured to the pivot-shaft N, held in fixed bearings, and to the upper end of

one of the arms M is attached the rod O, the outer end of which is provided with a screw-thread whereby by means of the nut 55 O' the pulley K⁵ may be moved backward to either tighten or loosen the belt K' when required. The tilting frame F is provided with the downwardly-extending arm F', to the side of which the opposite ends of the driving-chain P are attached, the said chain passing over the idler sprocket-wheel P' and being driven by means of the sprocket-wheel Q, secured to the hub of the gear-wheel Q', which is held for rotation upon the stud Q², secured 60 to the sliding plate Q³, which plate is adjusted for tightening the chain by means of the screw Q⁴. The gear-wheel Q' is actuated by means of the gear R, secured to the shaft R', which extends from side to side of the machine, and 65 upon the shaft R' is secured the driven pulley R², which is to be operated in opposite directions in order to cause the required forward-and-backward movement of the saw-carriage H. The solid pulley S, provided with 70 a leather-covered face, is held in a frame S', which is pivoted to the rod c and provided with the weight S², whereby the said pulley will be caused to bear heavily upon the surface of the pulley R². The shaft T is held 75 in the bearings T' T' at the upper ends of the arms T² T², secured to the pivot-shaft T³, the said arms being actuated by means of the pedal-lever T⁴, the pedal d of which extends from side to side across the end of the machine, and to the shaft T is secured the pulley U, the said shaft being driven from the shaft U' of the driving-pulley K by means of the pulley V upon the said shaft, the pulley V' upon the shaft T, and the crossed belt V². 80 When the pulley U is in the position shown in Fig. 4, the pulley S will bear heavily upon the surface of the pulley R², with the driving-pulley U out of engagement. Now when the pulley U is brought forward by pressure 85 upon the pedal d the surface of the pulley U will be caused to engage with the surface of the weighted pulley S to cause its rotation and with it the rotation of the pulley R², and if the downward movement of the pedal is 90 continued then the yielding pulley S will be lifted from engagement with the surface of the pulley R² and the pulley U brought into engagement therewith to cause the move- 95 100

ment of the pulley R^2 in the reverse direction, and upon the release of the pedal from pressure the driving-pulley U will be carried back to its former disengaged position. When 5 the pulley U is brought into engagement with the pulley R^2 , the saw-carriage H will be brought forward to cut off the projecting end of the board placed upon the table B . The initial forward movement of the chain P by 10 its action upon the arm F' will serve to cause the tilting movement of the saw-holding frame F to produce the required upward movement of the saw above the plane of the surface of the table, a suitable limiting-stop 15 e being provided for such upward movement, and upon the engagement of the tilting frame F with the stop e the carriage H will be brought forward with the saw D in its elevated position to saw off the end of the board held upon 20 the table. Then by slackening up on the pedal d the pulley S will be allowed to drop to engagement with the surface of the pulley R^2 , with the pulley U still in engagement with the pulley S , whereby a reversed movement 25 will be imparted to the chain P , the initial reversed movement being utilized in causing the downward movement of the saw below the plane of the surface of the table through the action of the chain P upon the arm F' , as 30 shown in Fig. 3, and thereafter the carriage will be carried back to its former rearward position without engagement with the board, so that a board placed upon the table may be shoved forward for cutting while the saw is 35 being moved back by the action of the pulleys U and S upon the pulley R^2 , thus making a saving in time.

I claim as my invention—

1. In a sawing-machine, the combination of the saw-carriage, the tilting frame pivoted to 40 the carriage, the saw-arbor journaled to the tilting frame, the operating-chain connected with the tilting frame, and means for imparting movement to the operating-chain in both directions, to first cause a vertical move- 45 ment of the saw, and then a horizontal movement of the saw-carriage, substantially as described.

2. In a sawing-machine, the combination of the saw-carriage, the tilting frame pivoted to 50 the carriage, the saw-arbor journaled to the tilting frame, the pulley and shaft journaled to the carriage, the gear and pinion, upon the shaft and saw-arbor, the operating-chain connected with the tilting frame, and means for 55 imparting movement to the operating-chain in both directions, substantially as described.

3. In a sawing-machine, the combination of the saw-carriage, the tilting frame pivoted to the carriage, the saw-arbor journaled to the 60 tilting frame, the pulley and shaft journaled to the carriage, the gear and pinion upon the shaft and saw-arbor, the operating-chain connected with the tilting frame, means for imparting movement to the operating-chain in 65 reverse directions, the idler-pulley upon the saw-carriage, the main driving-pulley and the belt-tightening pulley, substantially as described.

BENJAMIN G. LUTHER.
